UNITED STATES PATENT OFFICE.

DAVID MCNAIR, OF BOSTON, MASSACHUSETTS, ASSIGNOR TO ROXBURY CARPET COMPANY, OF SAME PLACE.

DESIGN FOR CARPET.

Specification forming part of Design No. 11,200, dated May 13, 1879; application filed April 19, 1879.
[Term of patent 3½ years.]

To all whom it may concern:

Be it known that I, DAVID MCNAIR, of Boston, in the county of Suffolk and State of Massachusetts, have invented a new and original Design for Carpets, of which the following is a specification.

My design is fully illustrated in the accompanying photographic illustration, forming a part of this specification.

The design consists of an ornamented figure, a, representing a Chinese building or pagoda, having a balcony, a', and various floral designs, b c d, surrounding the figure a.

I claim—

The design for carpets, consisting of the ornamented pagoda-like figure a and the surrounding floral designs b c d, as set forth.

In testimony whereof I have signed my name to this specification in the presence of two subscribing witnesses this 9th day of April, 1879.

DAVID MCNAIR.
